(57) **CLAIM**

The ornamental design for a watch holder, as shown and described.

DESCRIPTION

FIG. 1 is a perspective view of a watch holder showing my new design;

FIG. 2 is a side elevational view of one side of the watch holder shown in FIG. 1;

FIG. 3 is a side elevational view of the other side of the watch holder shown in FIG. 1;

FIG. 4 is a top plan view of the watch holder shown in FIG. 1;

FIG. 5 is a bottom plan view of the watch holder shown in FIG. 1;

FIG. 6 is a front elevational view of the watch holder shown in FIG. 1; and,

FIG. 7 is a rear elevational view of the watch holder shown in FIG. 1.

The broken lines in the drawings are used to show an unclaimed watch band and unclaimed portions of the watch holder.
